UNITED STATES PATENT OFFICE.

ROBERT F. SCHMIDT, OF NEW MARKET, ONTARIO, CANADA, ASSIGNOR TO YAWMAN AND ERBE MANUFACTURING COMPANY, OF ROCHESTER, NEW YORK, A CORPORATION OF NEW YORK.

BOX-FASTENER.

1,101,886.

Specification of Letters Patent. Patented June 30, 1914.

Application filed December 7, 1910. Serial No. 596,086.

To all whom it may concern:

Be it known that I, ROBERT FRANK SCHMIDT, of New Market, Province of Ontario, Canada, have invented certain new and useful Improvements in Box-Fasteners; and I do hereby declare the following to be a full, clear, and exact description of the same, reference being had to the accompanying drawings, forming a part of this specification, and to the reference-numerals marked thereon.

My present invention relates to fasteners and to boxes and it has for its object to provide a simple, light, cheap and convenient form of fastener for use in connecting together sheets of wood, paper, cardboard or similar material but more particularly such material as is used in the construction of storage or shipping boxes or packages, the improvements being of such a nature as to be particularly useful in the manufacture of folding or knock-down boxes.

To these and other ends the invention consists of certain improvements and combinations of parts all as will be hereinafter more fully described, the novel features being pointed out in the claims at the end of the specification.

In the drawings: Figure 1 is a perspective fragmentary view of a box constructed in accordance with my invention, the wall portions thereof in connection with which the fastener is used being shown as they appear just before being folded to their proper positions; Fig. 2 is a similar view of the box completely set up with the fasteners in place; Fig. 3 is a section taken substantially on the line 3—3 of Fig. 2 showing one of the fasteners in elevation, and Fig. 4 is a perspective view illustrating the manner in which the fastener is applied to the box.

Similar reference numerals throughout the several figures indicate the same parts.

The device illustrated in the present embodiment of the invention shows the useful application of my improvements to a box such as is usually made of cardboard or heavy paper to constitute the outer casing or container of a letter file and as such it comprises a top wall 1, side walls 2 and a bottom wall 3, the present terminology thereof being suggested merely by the position of the box in the figures. These walls may be rigidly or foldably connected together according to the nature of the box.

To the side walls 2 are foldably connected, in the present instance, as by scoring extensions of the material thereof at 4, reinforcing flaps 5 which fold beneath a wall member 6 hingedly attached to the bottom 3 at 7, as shown in Fig. 3. Hinged to the top wall 1 by a score 8 or otherwise is an outer wall member or flap 9 which folds down against the inner wall member 6 and in this way the end wall of the present box is formed.

The inner wall member 6 has at its edge a slot or perforation 10 in the region of the score 7 and of the adjacent corner of the box when formed which the said score defines, while the outer wall member or hinged flap 9 is provided with a perforation 11 arranged in substantially the same vertical plane but out of alinement with the perforation 10 when the members are in superposed or overlapped positions.

The fastener that I employ is preferably composed of a strip 12 of thin pliable sheet metal or any other suitable material which may be readily bent but will hold to its bent shape with considerable persistency. One end 13 of the strip is doubled into a spaced parallel relationship with the body portion but the other end 14 extends outwardly therefrom while the fastener retains its original formation, as shown in full lines in Fig. 4 and in dotted lines in Fig. 3.

To apply the fastener, the end 13 is inserted in the aperture 10 when the flaps 5 and the wall member 6 have been folded down, as shown in Fig. 4, until it occupies the position shown in dotted lines in the figure in which it embraces the edge of the wall member. The end 13 then lies against the inner face of the latter to retain the fastener and the body portion flat against the outer face thereof. The outer wall member 9 is then folded down over the outwardly projecting end 14 of the fastener which end is passed through the perforation 11 and then clenched down against the outer face of said member to secure it, preferably in a direction which doubles it back upon the body portion whereat a rigid wall is formed and the box is complete.

I have herein shown two fasteners employed but any number can be utilized according to the size of the parts and the strain imposed.

It will be noted that while the securing

member has a clenched position on both sides of the wall or of the members that it holds together, the clenching operation is necessitated only upon one and that the outer and accessible side. This permits the whole operation to be readily done by hand rather than by automatic machinery.

I further contemplate use of the fastener in various ways on boxes wherever two substantially parallel or adjoining and overlapping members are employed. The blank for the fastener has no peculiar shape that requires a special die for its formation. On the other hand it can be produced in quantities by simply cutting off sections of a ribbon of metal.

I claim as my invention.

The combination with a box having an inner wall member and an outer wall member hinged at opposite edges of one side of the box to fold toward each other, the free edge of the outer member extending adjacent to the hinge of the inner member and

being provided with a perforation, and the inner member being provided with a slot 25 aligned with its inner face coincident with its hinge-line and opening on the corner of the box at the junction with a side wall, of a fastener comprising a pliable, flat metal strip having a doubled portion embracing the inner wall and adapted to be applied while in doubled condition by the insertion of the free end of one of the parts forming the doubled portion through the slot with a straight movement in the plane of the under face of the inner wall, and a securing portion extending outwardly from the outer part of the doubled portion and through the perforation in the outer wall, said portion being clenched against the outer face of the 40 latter by bending in a direction toward the hinge of the inner wall.

ROBERT F. SCHMIDT.
